UNITED STATES PATENT OFFICE.

MOSES G. LANDSBERG, OF CHICAGO, ILLINOIS.

DESIGN FOR A BOTTLE.

SPECIFICATION forming part of Design No. 12,861, dated April 11, 1882.

Application filed February 16, 1882. Term of patent 3½ years.

To all whom it may concern:

Be it known that I, M. G. LANDSBERG, of Chicago, in the county of Cook and State of Illinois, have originated and invented a new and useful Design for Bottles; and I do hereby declare that the following is a full, clear, and exact description thereof, reference being had to the accompanying drawings, forming a part of this specification.

10 The object of my present invention is to furnish a novel design for a bottle; and it consists in making the body of the bottle with four rectangular sides, having arched tops, two of the alternate faces or facets being left smooth; 15 or all four of the sides may be left plain; and in the arched spaces over the rectangular faces are represented respectively a shield, the figures 1876, a spread-eagle, and a rayed sun. The edges of the sides of the bottle are corrugated in lozenges, while the base is surrounded by a series of hexagons. The neck of the bottle represents the handle, and the shoulder of the body, of a bell, the bell being encircled midway by a ring of stars.

20 In the accompanying drawings, Figure 1 is a perspective view of my bottle; and Figs. 2 and 3 are views of two of the side faces, showing the figures 1876 and the shield, respectively, in the arches over the faces.

25 Referring to the drawings, A is the bottle, which I denominate the "Century," of which a represents one of the sides, with the rectan-

gular face b and the arch c, containing the figures 1876 or the representation of one of the several-named devices. The corners are shown 35 with the corrugations in the form of a series of lozenges, extending from the shoulder downward to the base, where the encircling-ring of hexagons is shown. The shoulder of the bottle forms the bell d, which is surrounded by 40 the circle of stars, and the neck is shaped into the handle e of the bell.

Having thus described my design for a bottle, I claim—

1. The design of a glass bottle of which the 45 body is four-sided, having rectangular faces surmounted by arched spaces containing the respective devices of the sun, a spread-eagle, a shield, and the figures 1876, the faces being separated from each other by the lozenge-shaped corrugations along the edges of the sides.

2. The shoulder of the bottle, shaped as a bell, and the neck as the handle of the bell, the said bell being surrounded midway by a 55 circle of stars.

In testimony that I claim the foregoing as my own I affix my signature in presence of two witnesses.

MOSES G. LANDSBERG.
